UNITED STATES PATENT OFFICE

SAMUEL SPECTOR, OF BROOKLYN, AND CHARLES B. WILLIAMS, OF NEW YORK, N. Y.;
SAID WILLIAMS ASSIGNOR TO SAID SPECTOR

DISPLAY DEVICE

Application filed April 5, 1929. Serial No. 352,781.

This invention relates to display racks and particularly to a revolving rack designed especially for holding rolls of linoleum or carpets so that they may be displayed in a minimum amount of space and readily inspected by the customer without putting the sales clerk to the task of lifting the heavy rolls of goods.

The invention has for its principal object 10 to provide a display rack for a plurality of heavy rolls of goods which are supported in upright position and which may be unwound from the rolls by simply causing the latter to revolve in their holders.

15 A further object of the invention is to provide means attachable to the rack for aiding the operator to insert the heavy rolls one at a time into the device without the necessity of lifting the roll or rolls off the floor.

20 We accomplish these objects by means of the apparatus consisting of a certain combination and arrangement of parts, hereinafter fully described, set forth in the appended claims and illustratively exemplified in the 25 accompanying drawings, in which Figure 1 is a side elevational view of a display rack constructed in accordance with our invention; Figure 2 is a fragmentary plan view of the top of the rack; Figure 3 is a substantially 30 longitudinal sectional view of the lower end of the rack taken on lines 3-3 of Figure 4; Figure 4 is a substantially transverse sectional view taken on lines 4-4 of Figure 3; and Figure 5 is a longitudinal sectional view of 35 the inclined ramp over which the heavy rolls are guided to the rack, the view being taken on lines 5-5 of Figure 4.

Referring to the drawings, 10 denotes a disc shaped base supporting a ball bearing 40 turn table 11 at its center and a concentric metal track 12 adjacent the periphery. Attached to and supported on the upper plate 13 of the turntable 11 is the revolving roll display holder 14, which comprises a pair of vertically spaced discs 15 of the diameter corresponding with that of the base 10, a core or center post 16 and a plurality of equally spaced marginally disposed braces or spacing pipes 17. The ends of both the center 50 post 16 and pipes 17 are provided with lateral

flanges secured to the opposite faces of the two discs 15, as illustrated in Figure 4.

The upper disc 15 is provided with a plurality of radially cut slots 18 which are equally spaced from each other and extend 55 from the periphery well toward the center. Insertable plugs 19 are provided to close the outer portions of the slots 18 to prevent the rolls being mounted at their upper ends in the slots from working their way out. The lower disc 15 is provided with the same number of radially disposed grooves 20 as there 60 are slots 18 and the discs 15 are arranged relatively to each other so as to bring a slot 18 directly over and in line with a groove 20. Each groove 20 is provided on its opposite 65 walls with inverted L-shaped irons 21, the lateral arms forming flanges overlying the groove and their adjacent sides being spaced apart to form a slot 22.

70 The rolls of goods 23 are supported in upright position between the carrier discs 15 and at opposite ends the rolls are provided with bearing discs or flanges 24, each thereof 75 having a cylindrical centering block 25 which projects into the opening in the end of the roll. The discs 24 placed on the upper ends of the rolls are provided on their faces opposite the blocks 25 with upwardly projecting pins 26 which project through and turn in 80 their respective slots 18. The lower discs 24 carry flat plates 27 on their faces opposite the blocks, and the center of each plate is provided with an outwardly curved bearing surface or bulge 28 which rests and turns on the 85 flanges of the L-irons of the grooves 20, as illustrated in Figure 3. A bolt 29 projects axially of the block 25, disc 24 and bearing 28 and then between the walls of the slot 22, 90 where the head of the bolt engages under the lateral arms or flanges of the irons 21. After a roll 23 is placed in the rack a flat bar 30 having a slot in one end and a hook in the other is inserted between the lower disc 95 carrier 15 and flange end 24, the slot being placed over a pin 31 in the disc 15 at one side of the flange 24 and the other end swung into position in front of the bolt 29 and the hook end engaged against another pin 32 fixed in 100 upright position on the revolving carrier

disc. The under surface of the lower disc 15 is provided with a plurality of casters 32, which encircle the base 10 on the track 12, and which support the disc evenly about its periphery.

5 To insert a new full roll of goods 23 into place in the rack, an inclined platform or ramp 33 is used, the latter comprising a block triangular in longitudinal section, and having a center groove 34 flanged by strips of L-shaped irons 35 which are adapted to join with the irons 21 of any groove 20 in the lower disc carrier 15 and which follow the inclination of the block from the floor level 10 to that of the upper surface of the disc. A plurality of rollers 36 are mounted in the inclined face of the block and the higher end of the latter is concaved to receive the curve of the disc 15 against which it is held when 15 in use, as illustrated in Figure 4. Projecting from the curved end of the ramp and at each side thereof, are arms 37 which fit in between a pair of spaced blocks 38 depending from the under face of the lower disc 15. 20 A pair of blocks 38 is arranged on the disc 15 for each set of grooves 20, so that the ramp may be properly centered before any groove 20 of the rack. The ramp, after being placed in position so as to bring its groove 25 into register with the groove of the lower disc 15, is locked in position by means of hooks 39 and eyes 40, the latter being arranged at spaced distances on the periphery of the disc 15.

30 35 To first load the rack the ramp 33 is arranged in position before each groove 20, the end flanges or discs 24 attached to the ends of the roll 23 and the latter stood on end before the ramp. By tilting the roll and 40 pushing it toward the ramp the headed end of the bolt 29 enters the groove 34 and the lower disc 24 rests upon the rollers 36. Slight effort is required to push the roll up the incline over the rollers 36, as illustrated in 45 Figure 5, until the bolt enters the groove 20 and the pin 26 enters the slot 18 in the upper disc 15. The plug 19 is then put in place in the end of the slot 18 in the upper disc 15, while the bar 30 is swung to position on the lower disc 15 in front of the bulge 28 to prevent the roll from working its way out of the 50 rack when being rotated to remove the goods. This step is repeated until all the stations are provided with rolls, whereupon the ramp is taken from the machine until such time as it is necessary to refill with a new roll.

55 In addition to the foregoing, our invention contemplates and encompasses not only display racks circularly built but such as may comprise a plurality of units embodying the principles herein disclosed, wherein the said units are placed side by side adjacent each other, or in any other desirable arrangement. This construction may be modified so that

the units may be built in sections of one or more racks in each section and the sections later secured together.

Having now described our invention, what we claim and desire to secure by Letters Patent is:

1. A display device for rolled goods, comprising a fixed base, a revolving carrier rack mounted on the base comprising spaced discs having correspondingly disposed radial guideways, flanges for the ends of the rolled goods having projections to be inserted and then rotate in said guideways, and an inclined ramp attachable to the device before any one of said guideways for guiding a roll from the floor to the entrance of the guideway.

2. A display device for holding rolled goods in upright position, comprising a fixed base, a revolving carrier rack mounted on said base comprising spaced discs and intermediate upright spacing posts, radially disposed straight flanged grooves in the lower most disc and slotted guideways in the upper disc and flange plates for the opposite ends of the rolls of goods, each plate having a cylindrical block on one face to be inserted into the opening in the end of the roll and a projecting pin on the other face to center in a guideway.

3. A display device for holding rolled goods in upright position, as claimed in claim 2, including means carried by the revolving discs to prevent the pins from accidentally working out of their respective guideways.

4. A display device for holding rolled goods in upright position, as claimed in claim 2, in which the base is provided with an annular track and the lower disc of the rack carries a plurality of casters arranged to ride on said track during rotation of the rack.

5. A display device for holding rolled goods in upright position, as claimed in claim 2, in which the lower disc of the rack is provided with depending guide blocks on its under face, said blocks being arranged in pairs, one block on each side of each of the grooves in the lower disc, and a ramp attachable to the rack and having projections to be inserted between the blocks of each pair, said ramp having a guideway to register with a guideway of the lower disc to guide a roll from the floor to the rack and rollers upon which the lower flange of the roll rests in its travel from the floor to the rack.

6. A display device, as claimed in claim 2, including an inclined ramp having a guideway to lead from the floor level to the lower disc of the rack and means for detachably connecting the ramp in position before any guideway.

7. An inclined ramp for elevating rolled goods on end, having an inclined flanged groove centrally and longitudinally thereof, rollers on opposite sides of the groove over

which the end of the roll travels, and means
for detachably connecting the ramp to a plat-
form.

In testimony whereof they have affixed
5 their signatures.

SAMUEL SPECTOR.
